(57) **CLAIM**

The ornamental design for an automated pallet system, as shown and described.

DESCRIPTION

FIG. 1 shows a perspective top right view of an automated pallet system.

FIG. 2 shows a front view of the automated pallet system.

FIG. 3 shows a left view of the automated pallet system.

FIG. 4 shows a right view of the automated pallet system; and,

FIG. 5 shows a top view of the automated pallet system.
